W. J. KENT.

EAR SHIELD.

APPLICATION FILED JULY 16, 1918.

Patented Feb. 8, 1921.

Inventor.

William J. Kent,

By his Attorney.

Ernest Thompson

UNITED STATES PATENT OFFICE.

WILLIAM J. KENT, OF BROOKLYN, NEW YORK, ASSIGNOR TO THE MECHANICAL RUBBER COMPANY, A CORPORATION OF NEW JERSEY.

EAR-SHIELD.

1,367,746.

Specification of Letters Patent.

Patented Feb. 8, 1921.

Application filed July 16, 1918. Serial No. 245,225.

To all whom it may concern:

Be it known that I, WILLIAM J. KENT, a citizen of the United States, residing in the borough of Brooklyn, city of New York, county of Kings, and State of New York, have invented certain new and useful Improvements in Ear-Shields, of which the following is a full, clear, and exact description.

This invention relates to a device adapted 10 to support a telephone receiver in operative position with relation to the ear and to prevent extraneous sounds from interfering with the proper operation of the instrument and the hearing of the user. The device is 15 particularly adapted for use by aviators, who heretofore have experienced considerable difficulty in hearing the messages transmitted by telephone, due to the noises of the engine, the explosions of shells, and other 20 sounds which act to interrupt the operation of the receiver and confuse the hearing.

An object of the present invention is to provide a light, flexible ear shield adapted 25 to support a telephone receiver in operative position with relation to the ear and to protect the ear and the receiver from the action of undesirable sounds, thus enabling the user to hear messages distinctly.

Referring to the drawings wherein one of 30 the various embodiments of the invention is illustrated:

Figure 1 is a bottom plan view of the shield;

Fig. 2 is a cross-section of the shield taken 35 on the line 2—2 of Fig. 1, and

Fig. 3 is a view showing the shield in position upon the head of a wearer.

The ear shield illustrated in the drawings comprises a substantially disk-shaped integral construction formed of fabric and rubber or other suitable yielding material 40 adapted to conform to the configuration of the side of the head of the user.

The outer face 10 of the shield is made substantially dome-shape for the purpose of avoiding resistance to the passage of the shield through the air when in use.

The inner face 11 of the shield is formed with a centrally disposed circular cavity 12 50 shaped to hold a telephone receiver 13, embodying a cylindrical casing 14 having a flat back wall 15. The bottom 16 of the cavity is concave in shape and is formed of elastic material, so that when the flat back wall of 55 the receiver is pressed against it, in fitting

the receiver in place, it will tend to flatten causing a portion of the air between it and the back of the receiver to be expelled. When the pressure upon the receiver is released, the bottom of the cavity will spring 60 away from the back of the receiver creating a partial vacuum between the parts, thus developing a suction that operates to hold the receiver in position. The partial vacuum also serves to prevent the transmission of 65 undesirable sound waves to the receiver, insuring the proper operation of the instrument.

Arranged on the inner face of the shield and spaced from the receiver cavity is an 70 elliptical rib 17 of elastic material, that forms the side walls of a cavity of sufficient size to contain the ear. This rib is made of greater height on one side of the ellipse than on the other to adapt it to contact at all 75 points with the head. The higher portion 18 of the rib is adapted to meet the sloping portion of the head at the back of the ear.

Disposed between the rib 17 and the outer edge of the shield is a concave recess 19, 80 which extends completely around the shield. This recess adapts the outer margin of the shield to yield to snugly engage the head of the wearer. When the shield is applied, the ear is disposed within the cavity bounded by 85 the elliptical rib, and the outer margin of the shield shapes itself to the side of the head. By reason of the close fit of the rib 17 to the head, the air pocket extending around the rib in the recess 19, and the close 90 fit of the outer margin of the shield to the head, sound waves emanating outside of the shield are prevented from entering the ear cavity thereof and interfering with the operation of the receiver and the proper hearing of messages transmitted thereby.

As an additional means of preventing undesirable sound waves from entering the shield, there is provided between the inner and outer faces thereof an air chamber 20 100 which is spaced from and extends completely around the receiver cavity 12. This chamber is preferably filled with air or gas under pressure and this may be done in any suitable manner as disclosed for instance in 105 United States patent to Gross, 483,718, October 4, 1892. The action of the pressure within the chamber serves to hold the walls of the chamber in a distended position, thus strengthening the shield without destroying 110

- its flexibility, and enabling a light construction to be employed. Although it is preferred to fill the chamber with fluid under pressure, it is within the contemplation of 5 the invention to create a partial vacuum therein, the tendency of the chamber to collapse being sufficiently resisted by the vulcanized rubber composition constituting the surrounding walls.
- 10 Any suitable means may be used for securing the shield to the head, for example, straps may be provided, or the shield may be directly secured to a helmet or other head gear.
- 15 While one of the preferred embodiments of the invention has been described, it is to be understood that various modifications in material, form, and arrangement may be resorted to without sacrificing any of the advantages or departing from the spirit and scope of the invention defined in the following claims.
- Having thus described my invention what I claim and desire to protect by Letters 25 Patent is:
1. A shield for excluding sounds from the ear having an imperforate outer wall and an inner wall adapted to conform to one's head around the ear, said inner wall within 30 its margins being shaped to grip and retain a telephone receiver and being united marginally to the outer wall.
  2. A sound excluding shield having externally and internally spaced walls united 35 marginally and centrally and shaped within its margins to retain and inclose all but one side of a telephone receiver, said inner wall being provided with a yielding rib adapted to encircle one's ear and to conform to the 40 head thereabout.
  3. An ear shield having a cavity shaped to receive the ear of the user of the shield, a cavity communicating therewith shaped to hold a telephone receiver, a third cavity 45 rounding said ear receiving cavity, and an inclosed fluid tight chamber surrounding said telephone receiver cavity.
  4. An ear shield having a cavity shaped to receive the ear of the user of the shield, 50 a cavity communicating therewith shaped to hold a telephone receiver, and an inclosed fluid tight chamber surrounding said cavities.
  5. An ear shield having a head engaging 55 face provided with a cavity having cylindrical walls adapted to receive and hold in place a telephone receiver, said cavity having a dome-shaped end wall providing an air space.
  6. An ear shield having a head engaging 60 face provided with a cavity having elastic cylindrical walls adapted to closely receive and hold in place a telephone receiver, and having an elastic dome-shaped end wall providing an air space.

7. An ear shield having a head engaging face provided with substantially concentric elastic head engaging ribs.

8. An ear shield comprising a dome-shaped elastic outer wall, and substantially 70 concentric elastic head engaging ribs.

9. An ear shield having a fluid tight chamber within its walls, a cavity adapted to hold a telephone receiver, a second cavity adapted to receive the ear of the user of the 75 shield, and a third cavity spaced from and disposed in a plane with said ear receiving cavity.

10. An ear shield having an annular fluid tight chamber within its walls, a cavity 80 adapted to hold a telephone receiver, a second cavity adapted to receive the ear of the user of the shield, and a third cavity spaced from and disposed in a plane with said ear receiving cavity.

11. An ear shield having a cavity adapted to hold a telephone receiver said cavity having a concave yielding bottom wall, a second cavity adapted to receive the ear of the user 90 of the shield, and a third cavity spaced from and disposed in a plane with said ear receiving cavity.

12. An ear shield having a fluid tight chamber within its walls, a cavity adapted to hold a telephone receiver said cavity having a concave yielding bottom wall, a second cavity adapted to receive the ear of the user 95 of the shield, and a third cavity spaced from and disposed in a plane with said ear receiving cavity.

13. An ear shield having a yielding outer margin adapted to conform to the shape of the side of the head of the user of the shield, a cavity adapted to hold a telephone receiver, and a continuous rib of yielding material 105 constituting the side walls of an ear receiving cavity.

14. An ear shield having a yielding outer margin adapted to conform to the shape of the head of the user of the shield, a cavity 110 adapted to hold a telephone receiver, and a continuous rib of yielding material constituting the side walls of an ear receiving cavity, portions of said rib being of varying heights to adapt the rib to fit the side of the head of 115 the user of the shield.

15. An ear shield having a continuous and generally convex outer wall and an elastic inner wall united thereto marginally and adapted within its margins to yieldingly engage one's head entirely about the ear, said inner wall being cupped centrally to hold a telephone receiver and being fashioned to permit retention of the receiver in part at least by vacuous action between it and the 120 outlying body of the shield.

Signed at New York, N. Y., this 27th day of June, 1918.

WILLIAM J. KENT.
